UNITED STATES PATENT OFFICE

134,428

DESIGN FOR AN INKSTAND

Gustav J. Sengbusch, Milwaukee, Wis.

Application September 28, 1942, Serial No. 108,345

Term of patent 7 years

To all whom it may concern:

Be it known that I, Gustav J. Sengbusch, a citizen of the United States, residing at Milwaukee, in the county of Milwaukee and State of Wisconsin, have invented a new, original, and ornamental Design for an Inkstand, of which the following is a specification, reference being had to the accompanying drawing, forming part thereof.

In the drawing:

The figure is a perspective view of an inkstand embodying my new design.

I claim:

The ornamental design for an inkstand, as shown.

GUSTAV J. SENGBUSCH.
